(57) **CLAIM**

The ornamental design for a cutlery holder, as shown and described.

DESCRIPTION

FIG. 1 is a perspective view of a novel cutlery holder designed in accordance with the present invention;

FIG. 2 is a top plan view of the cutlery holder of FIG. 1, illustrating a variety of different slots to accommodate cutlery tools;

FIG. 3 is a front elevation of the cutlery holder of FIG. 1;

FIG. 4 is a rear elevation of the cutlery holder of FIG. 1;

FIG. 5 is a left side elevation of the cutlery holder of FIG. 1;

FIG. 6 is a right side elevation of the cutlery holder of FIG. 1;

FIG. 7 is a bottom plan view of the cutlery holder of FIG. 1; and,

FIG. 8 is a stylized block having slots for receipt of a variety of kitchen tools, i.e., knives and scissors.

The broken lines are for illustrative purposes only and form no part of the claimed design.
